FLASHER

William Huppert, New York, N. Y., assignor to
 Ampex, Inc., New York, N. Y., a corporation of
 New York

Application November 2, 1932, Serial No. 640,749

9 Claims. (Cl. 200—115.5)

This invention relates to flashers, and is directed to a combination fitting having a receptacle portion for receiving the base of a lamp, and a screw threaded plug portion adapted to be screwed into any suitable outlet receptacle or socket.

An object of this invention is to provide a highly improved miniature flasher of the character described provided with an insulating housing for a screw receptacle and a screw plug attached to the housing, the construction being such that the parts may be readily and easily assembled into a compact, strong and rugged structure.

A further object of this invention is to provide a flasher of the character described which shall be relatively inexpensive to manufacture, comprise few and simple parts and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible embodiments of this invention,

Fig. 1 is a side elevational view of a flasher device embodying the invention;

Fig. 2 is an axial sectional view of the device shown in Fig. 1;

Fig. 3 is a fragmentary, enlarged, detail cross-sectional view of a portion of the thermostatic unit;

Fig. 4 is a front elevational view of the thermostatic unit and connector before assembling in the device; and

Fig. 5 is a cross-sectional view taken on line 5—5 of Fig. 1.

Referring now in detail to the drawing, 10 designates an electric fitting embodying the invention, here shown for the purpose of illustration only in the form of a miniature flasher.

The device 10 comprises an insulating housing 11 having a tubular wall 12 provided with an outwardly flaring rim or mouth portion 13 and a rear end wall 14 having a central opening 15. The wall 14 is provided with a shoulder or annular step 14a on the outer surface thereof for the purpose hereinafter appearing. The outer surface of the tubular wall 12 furthermore, is formed with parallel corrugations 12a preferably extending from the mouth portion 13 to the shoulder.

The corrugations 12a may be of any suitable shape to form grooves and ridges whereby the outer surface of said tubular portion 12 is non-circular in transverse cross-section, as shown in Fig. 5 of the drawing.

Within the housing 11 is mounted a screw shell 16 for receiving the base of a lamp. Attached to the rear end of the screw shell 16 is an insulating disc 17 of any suitable construction and preferably provided with a slot 18 for the purpose hereinafter stated.

Attached to the rear end of the housing 11, is a member 20 made of sheet metal and having a screw threaded plug portion 21 adapted to be screwed to a screw threaded socket or receptacle. Extending from the lower end of the portion 21 is a stepped portion 22 engaging the stop 14a of the rear wall 14; and extending from said step portion 22 is a corrugated skirted portion 24 frictionally engaging the corrugated surface 12a of the member 20. Thus the member 20 non-rotatably engages the housing 11. Of course, the member 20 may be pulled off the housing 11 and then remounted in another angular position, since the corrugations of the skirted portion 24 are similar to the corrugations 12a.

Seated on the rear or upper end of the screw threaded portion 21, is an insulating disc 25 formed with a slot 26 preferably substantially parallel to the slot 18 in the disc 17. It will be noted that the tubular shells 21 and 16 are substantially coaxial and that the slots 18 and 26 are substantially aligned with the opening 15 of said rear wall 14.

A strip of metal or wire 29 may be soldered at one end 30 thereof to the rear end of the shell 12, said strip extending through the opening 15 and being bent over against the rear surface of the wall 14. The outer end 32 of said strip 29 is bent over the step 14a and disposed between said step and the step 22 of the metallic member 20. The shell 16 is thus electrically connected to the screw threaded portion 21 of the member 20.

Interconnecting the insulating discs 17 and 25 is a combination connector and thermostatic unit 35 shown in Figs. 2, 3, and 4 of the drawing. The connector 35 comprises an elongated strip of metal 36 the lower end whereof substantially contacts the disc 17. The upper end 37 of said strip 36 passes through the opening or slot 26 and is bent over the top or upper surface of the disc 25. Said strip 36 is furthermore provided with a contact point 38 adjacent the upper end thereof and with a hole or opening 39 adjacent the lower end there-

of. Fixed to the lower end of the strip 36 is a thermostatic unit 40 comprising a bi-metallic strip 41, the lower end 42 of which extends through the slot 18 in disc 17 and is bent against the under-
5 side of said disc. Interposed between the lower end of the strip 41 and the lower end of the strip 36 is an insulating washer 43. The bi-metallic strip 41 is furthermore formed with an opening 44, coaxial with the opening 39 in the strip 36,
10 receiving a bushing 45, said bushing passing through the opening in the insulating washer 43. The strip 36, the washer 43, the bushing 45 and the strip 41 are attached together by a metallic eyelet or rivet 46. It will thus be noted that the
15 thermostatic bi-metallic strip 41 is insulated from the lower end of the strip 36 by the bushing 45 and washer 43.

Received over the bi-metallic strip 41 is a wrapper or sleeve 50 of asbestos or the like heat
20 resisting material and wound around said sleeve 50 is a heating coil or wire 51 having one end thereof attached to the bi-metallic strip 41, and the other end 53 thereof attached to the strip 36. The strip 36 may be formed with an in-
25 clined slit 54 in one edge thereof to provide a prong 55 bent out of the plane of said strip 36 to form a wedge for receiving the end 53 of the heating wire 51. In other words, the upper end of the wire 51 may merely be placed in the wedg-
30 ing groove or slit 54 and pressed downwardly for causing said end of the wire to be firmly attached to the connector strip 36.

It will now be understood that the insulating discs 17 and 25 are firmly attached together by
35 means of the connector 3 since the upper end of the strip 3 is bent over the upper disc 25 and the lower end of the thermostatic strip 41 is bent over the lower disc 17. The bent over portion 37 forms a central contact for the plug
40 shell 21 and the bent over portion 42 of the bi-metallic strip 41 forms a central contact for the shell 16. The current passes through the central contact 37 to the strip 36 and then through the heating coil or wire 51 to the bi-metallic
45 strip 41, and hence to the central contact 42. The coil thus becomes heated to cause the contact point 60 on the upper end of the strip 41 to contact the contact point 38 whereby the current is short circuited from the heating coil
50 to permit the strip 41 to bend away from the strip 36, this action being repeated alternately.

It will thus be seen that there is provided a device in which the several objects of this invention are achieved, and which is well adapted
55 to meet the conditions of practical use.

As various possible embodiments might be made of the above invention, and as various changes might be made in the embodiment set forth, it is to be understood that all matter herein set forth or shown in the accompanying drawing, is to be interpreted as illustrative and not in a limiting sense.

Having thus described my invention, I claim as new and desire to secure by Letters Patent:—

65 1. An electric fitting comprising a tubular insulating housing having an end wall at the rear end thereof and being open at the front end thereof, said end wall being formed with a central opening, a lamp base receiving shell within
70 said housing, and a member made of sheet metal having a screw threaded plug portion, a portion abutting the rear end surface of said housing, extending from said plug portion, and a skirted portion extending from said last portion
75 frictionally receiving the rear end portion of said

housing, said screw shell and screw threaded plug portion each having an insulating disc at the rear end thereof, a conductor interconnecting said shell with said sheet metal member, and a thermostatic unit interconnecting said insulating discs and extending through the opening in said end wall.

2. A flasher comprising a tubular insulating housing, a lamp base receiving screw shell within said housing, said screw shell having an insulating disc at the rear end thereof, a member having screw threaded plug portion provided with an insulating disc at the rear end thereof and disposed coaxial with said screw shell, a skirted portion extending from said plug portion receiving the rear end portion of the housing, a conductor interconnecting the screw shell with said plug portion, and a metallic tie strip interconnecting said insulating discs and being the only means for attaching said member to said housing.

3. A flasher comprising a tubular insulating housing having a mouth at the front end thereof, a lamp base receiving screw shell within said housing, a member made of sheet metal having a screw threaded plug portion, a portion extending from said plug portion abutting the rear end of said housing and a skirted portion extending from said last portion receiving the rear end portion of said housing, a conductor interconnecting said screw shell and said sheet metal member, insulating discs at the rear ends of said screw shell and screw threaded plug portion, and a tie member interconnecting said insulating discs and constituting the sole means for attaching said sheet metal member to said housing, and having portions forming central contacts for said discs.

4. A flasher comprising a tubular insulating housing having a mouth at the front end thereof, a lamp base receiving screw shell within said housing, a member made of sheet metal having a screw threaded plug portion, a portion extending from said plug portion abutting the rear end of said housing, and a skirted portion extending from said last portion receiving the rear end portion of said housing, a conductor interconnecting said screw shell with said sheet metal member, insulating discs at the rear ends of said screw shell and screw threaded plug portion, and a thermostatic unit interconnecting said insulating discs and constituting the sole means for attaching said sheet metal member to said housing, and having portions forming central contacts for said discs.

5. An electric fitting comprising a tubular insulating housing having a mouth portion, and an outer surface formed with parallel, longitudinal corrugations, and a metallic member having a screw threaded plug portion, a portion abutting the rear end of said housing, and a skirted portion formed with longitudinal corrugations receiving a portion of the corrugated surface of said housing, a screw shell within said housing and having an insulating disc at the rear end thereof, an insulating disc at the rear end of said screw threaded plug portion, a conductor strip interconnecting said screw shell with said metallic member, and a thermostatic unit interconnecting said insulating disc and constituting the sole means for attaching said housing to said metallic member.

6. An electric fitting comprising a tubular insulating housing having a mouth portion, and an outer surface formed with parallel, longitudinal

corrugations, and a metallic member having a screw threaded plug portion and a skirted portion formed with longitudinal corrugations receiving a portion of the corrugated surface of said housing, a screw shell within said housing and having an insulating disc at the rear end thereof, an insulating disc at the rear end of said screw threaded plug portion, a conductor strip interconnecting said screw shell with said metallic member, and a thermostatic unit interconnecting said insulating discs, said unit comprising an elongated metallic strip having a portion extending through a slot in said second disc and bent over the rear surface of the latter, a bi-metallic thermostatic strip attached at one end thereof to the other end of said first strip and insulated therefrom, said bi-metallic strip having an extension passing through a slot in the first insulating disc and bent over the underside of the latter, and a heating coil disposed about said bi-metallic strip and having one end thereof contacting said strip and the other end thereof engaging said first strip.

7. An electric flasher comprising a tubular insulating housing having a mouth at one end thereof, a lamp base receiving shell within said housing, and a member made of metal having a screw threaded plug portion and a skirted portion extending from said plug portion frictionally receiving the other end of said housing, slotted insulating discs at the rear ends of said screw shell and screw threaded plug portion, a conductor interconnecting said shell with said member, and a thermostatic unit interconnecting said insulating discs, said unit comprising an elongated strip of metal having one end thereof passing through the disc of said screw threaded plug portion, a bi-metallic thermostatic strip attached at one end thereof to the opposite end of said first strip and insulated therefrom, said bi-metallic strip having an extension passing through the slot of the other insulating disc, a sleeve of heat resisting material disposed about said bi-metallic strip and a heating coil wound around said sleeve

and having one end thereof attached to said bi-metallic strip, and the other end thereof attached to said first strip.

8. A flasher comprising a tubular insulating housing having a mouth at one end thereof and formed with a rear end wall at the opposite end thereof, a lamp base receiving screw shell within said housing, a member made of sheet metal having a screw threaded plug portion disposed coaxially with respect to said screw shell and abutting the rear end of said insulating housing, insulating discs at the rear end of the said screw shell and at the rear end of said screw threaded plug portion, and a thermostatic unit interconnecting said insulating discs. 15

9. An electric fitting comprising a tubular insulating housing having an end wall at the rear end thereof and being open at the other end thereof, said end wall being formed with a central opening, a lamp base receiving screw shell 20 within said housing, a member made of sheet metal having a screw threaded plug portion coaxial with said screw shell contacting the rear end of said housing, insulating discs at the housing of said screw shell and screw threaded plug 25 portion, a thermostatic unit interconnecting said insulating discs and extending through the opening in said end wall, said unit comprising an elongated strip of metal having one end engaging the disc on the screw threaded plug portion, said 30 strip passing through the opening in said end wall, a bi-metallic thermostatic element connected at one end thereof to the opposite end of said strip and being insulated therefrom, said bi-metallic element having an extension attached 35 to the insulating disc on said screw shell, the main portion of said bi-metallic element being co-extensive with said metallic strip, cooperating contact points at the free end of said bi-metallic element and on said metallic strip, and a heating 40 element wound about said bi-metallic element and attached thereto at one end thereof and at the other end thereof to said metallic strip.

WILLIAM HUPPERT.
